Primary Examiner — Thomas Johannes*Assistant Examiner* — Shawn T Gingrich(57) **CLAIM**

The ornamental design for the cable handler, as shown and described.

DESCRIPTION

FIG. 1 is a rear view of the cable handler;
FIG. 2 is a top view of the cable handler;
FIG. 3 is a top isometric view of the cable handler;
FIG. 4 is a bottom isometric view of the cable handler; and,
FIG. 5 is a front isometric view of the cable handler with a wing open.

The broken line portion of the figure drawings is included to show boundaries that form no part of the claimed design.
